UNITED STATES PATENT OFFICE.

FRANK E. BUTTON, OF NEW YORK, N. Y.

RAILWAY-SIGNAL.

SPECIFICATION forming part of Letters Patent No. 683,843, dated October 1, 1901.

Application filed August 9, 1900. Serial No. 26,331. (No model.)

To all whom it may concern:

Be it known that I, FRANK E. BUTTON, a citizen of the United States, residing at the city of New York, in the borough of Manhattan 5 and State of New York, have invented certain new and useful Improvements in Railway-Signals, of which the following is a full, clear, and exact description.

This invention relates to automatic railway 10 block-signals operating through the agency of electricity.

The object of the invention is to provide a system, adapted for either single or double track roads, which shall be simple and cheap 15 to install, certain in its operation, and safe to the greatest degree.

My improved system involves a signal at each end of a block, which is set to "danger" when a car or train enters the block from 20 either end, in combination with a second set of signals automatically operated when the first set are operated to indicate whether a second car or train is entering the block from the opposite direction at the same time. Acci- 25 dents on single-track roads sometimes occur from the fact that cars enter the opposite ends of a block simultaneously, thus preventing the motormen from distinguishing which of them set the signals and giving to each of 30 them the impression that his car or train was the instrumentality that accomplished this, and thus leading them into collision. The second set of signals referred to are intended to prevent this occurrence, as will be described 35 hereinafter.

The invention also consists of other combinations and constructions, which will be described, and pointed out in the claims.

In the accompanying drawings, Figure 1 is 40 a section of the road-bed and elevation of a signal-post. Fig. 2 is a section of the case containing the signal-operating mechanism and showing the latter in side elevation. Fig. 3 is a section on line x of Fig. 2. Fig. 4 illus- 45 trates the track instrument in detail. Fig. 5 is a diagram of the circuits. Fig. 6 shows a modification of the form of signal and the way of operating it.

The signal mechanism shown in Figs. 2 and 50 3 is for operating a semaphore. The arm is indicated by A. It is pivoted at a and is slightly counterbalanced by a spring a'. The

hub of the arm carries a lug a². Beneath the hub is mounted a disk b, having teeth b' on its periphery arranged some distance apart 55 and upon one face the ratchet-teeth b², there being twice as many ratchet-teeth as there are of the teeth b'. Upon the axis of the disk an arm c is pivoted and carries a pawl c', which engages with the ratchet b². The free 60 end of the arm connects with the core d' of a solenoidal electromagnet d, said core being normally held in its outer or withdrawn position by a spring d². When the magnet is energized, it pulls down on the arm c and rotates the disk the space of one ratchet-tooth. The lug a² on the semaphore projects into the path of the teeth on the disk and is arranged 65 so that with one movement of the disk the semaphore is allowed to fall to the danger position and with the next it is lifted to the safety position. The pawl b² prevents back- 70 ward movement of the disk.

At each end of a block the track is equipped 75 with a circuit-closer, consisting of a spring-supported bar e, placed along the side of one rail in position to be depressed by the wheels of a car and in electrical communication with the rail by any suitable means, such as the flexible conductor e'. Beneath this bar is an 80 insulated contact e², which it touches when it is depressed by the car-wheel.

Adjacent to each end of the block is a signal-post S, carrying a semaphore, and at some near location to each is another signal 85 or indicating device, such as the lamps f and f'.

Current to operate the signals can be taken from the feeder of a trolley system or from a special conductor run for the purpose. As 90 shown in the diagram, Fig. 5, the current is supposed to be supplied by a trolley system, of which G is the generator, from which the main conductor g leads along the road. At the beginning and ending of each block 95 branches 1 and 2, respectively, lead through the solenoid d to the corresponding insulated contact e², and these two branches are connected together by a circuit 3, which includes the lamps f and f', and is joined to the re- 100 spective branches 1 and 2 at points between the solenoid d and the contact e². The return-circuit to the generator is by the rails of the track.

The operation is as follows: When the block is clear, the semaphore stands in an upwardly-inclined position, as shown by the dotted lines. When a car enters the block 5 traveling from left to right, its wheels depress the bar e at the left end of the block to make contact with e^2 , whereupon a circuit is closed from conductor g through branch 1 to the rail-return and another circuit through 10 branch 2 and wire 3 to the rail-return. Since these two circuits are unevenly balanced as to resistance, the solenoids will be so constructed that they will move their respective cores when energized by such current as will 15 flow in the circuit of higher resistance and so that they will carry the heavier current flowing in the circuit of lower resistance. Hence when these two circuits are closed at the left end of the block both solenoids will 20 be energized and the disks b will be rotated the space of one ratchet-tooth, whereupon the tooth b' will pass from under the lug a^2 and allow the semaphores to fall to "danger." The circuits through the solenoids will be 25 held closed until the car or train has passed beyond the bar e , the bar being as long as the entire wheel-base of the car or train. When the last wheel leaves the bar, the circuits will open and the cores of the solenoids 30 will return to their elevated positions under the action of the springs d . When the car reaches the right-hand end of the block, the solenoids are again energized by the closure of the circuit at the bar e at that end of the 35 block, the lamps being then included in circuit with the left-hand solenoid. The disks are again turned the space of one tooth of the ratchet, whereupon a tooth b' pushes against the lug a^2 and elevates the semaphores, the 40 same being held in the elevated position by the tooth b , which remains beneath the lug, as shown in dotted lines in Fig. 2. Now as long as one car or train enters a block before another it will set the signals against any other 45 car or train approaching the block; but if at the instant one car is entering at one end another is entering at the other end the signals will go to "danger" just the same, but each motorman will become aware of the entry of 50 the other by the fact of the lamps not lighting. It will be seen that the cars on entering the block simultaneously will close the circuits through both of the branches 1 and 2 direct to the rail-return, and thus short-circuit the 55 lamps f and f' . Hence if the motorman observes that the lamps are not burning he will know another car is approaching him on the same track, and he can take the necessary precautions to avoid a collision. It will also be 60 observed that a failure of the lamps to light when a car enters a block might indicate a

break in the branch circuit 1 or 2 at the other end, and consequently that the signal there was not working, so that in any case a failure of the lamps to burn should mean "proceed 65 with caution."

The lamps f and f' are connected in multiple series to reduce to a minimum the possibility of the current failing to flow over the circuit 3, for it is highly improbable that a 70 lamp in each circuit would burn out at the same time.

As a means for indicating whether the signals are working properly or not a local circuit $o p$ for each block may be used. This circuit, which includes a battery q and an indicator r , has terminal points s and t at each semaphore, which are brought into contact each time the semaphore moves by means of the finger u moving against the lever t , and 75 thus operating the indicator r .

Fig. 6 shows means for operating a rotary signal, which may be a disk or plate rotating around a diametrical axis or a four-sided box having different colors painted on its sides. 80 Each movement of the ratchet rotates the signal a quarter-turn by means of the interposed gearing.

In all forms of signal it will be understood that lamps can be arranged as usual to indicate at night in place of the semaphores and that in place of the lamps f and f' other signaling devices may be used in the daytime.

Having described my invention, I claim—

1. In a railway signaling system, a block 95 provided at each end with normally open circuit-closers adapted to be momentarily closed by the cars, a main electric circuit, parallel branches respectively including said circuit-closers, and each including also electromagnetic signal-operating devices, and another branch circuit connecting the two parallel branches together and including other signal devices, substantially as described.

2. In a railway signaling system, a block 105 provided at each end with normally open circuit-closers adapted to be momentarily closed by the cars, a main electric circuit, parallel branches respectively including said circuit-closers, and each including also electromagnetic signal-operating devices, and another branch circuit connecting the two parallel branches together at points between said circuit-closers and the electromagnetic signal-operating devices, and including other signal 110 devices, substantially as described.

In witness whereof I subscribe my signature in presence of two witnesses.
